DISPLAY BLISTER FOR A PACKAGE OF RIBBON AND A BOW OR THE LIKE

Maurice C. Robinson, 16 Shornecliffe, Montreal,
Quebec, Canada

Filed Mar. 27, 1959, Ser. No. 55,225

Term of patent 14 years

(Cl. D58—2)

Figure 1 is a front perspective view of a display blister for a package of ribbon and a bow or the like embodying my new design; and

I claim:

The ornamental design for a display blister for a package of ribbon and a bow or the like, as shown.
